United States Patent Office.

CHARLES M. THEBERATH, OF NEWARK, NEW JERSEY.

Letters Patent No. 71,819, dated December 3, 1867.

IMPROVED HARNESS-MOUNTING.

The Schedule referred to in these Letters Patent and making part of the same.

TO ALL WHOM IT MAY CONCERN:

Be it known that I, CHARLES M. THEBERATH, of Newark, in the county of Essex, and State of New Jersey, have invented a new and useful Improvement in "Harness-Mountings;" and I do hereby declare that the following is a full, clear, and exact description thereof, which will enable others skilled in the art to make and use the same, reference being had to the accompanying drawing, forming part of this specification.

The present invention relates to the check-rein hooks of harnesses, and to other portions of such mountings as are capped with metal tips or knobs; and the invention consists in screwing said tips or knobs upon the end of the hooks in such a manner as to embrace and hold the end of the metal lining to the hook, terminating at said knob or tip.

In the accompanying plate of drawings, my improvement in harness-mountings is illustrated, the figure being a side view of a check-rein hook, having its end tipped or capped according to the present invention.

A, in the drawings, represents a check-rein hook, which may be of any of the ordinary forms of such hooks. B, the metal lining to the hook, terminating at its end, C, where, in connection with the end of the hook, a screw-thread is formed around it so as to receive the knob or tip D, suitably constructed to screw on and over the same, thus securing and holding the metal lining, as plainly shown in the drawings.

I claim as new, and desire to secure by Letters Patent—

The end of the hook A and lining B, provided with a screw-thread, upon which the top D is screwed to retain said lining in position against the hook, as herein shown and described.

CHARLES M. THEBERATH.
